CLAIM

The ornamental design for a power controller labeling scheme, as shown and described.

DESCRIPTION

FIG. 1 is a front view of labels reading from left to right of the power controller labeling scheme showing our new design; and,

FIG. 2 is a front view, rotated clockwise 90° from FIG. 1, of the labels still reading from left to right thereof.

1 Claim, 2 Drawing Sheets

FIG. 1

FIG. 2
